UNITED STATES PATENT OFFICE

JOHN HERZOG, OF SAGINAW, MICHIGAN

DESIGN FOR A TYPEWRITER CABINET DESK

Application filed September 8, 1931. Serial No. 41,042. Term of patent 7 years.

To all whom it may concern:

Be it known that I, JOHN HERZOG, a citizen of the United States, residing at Saginaw, county of Saginaw, State of Michigan, have invented a new, original, and ornamental Design for Typewriter Cabinet Desk, of which the following is a specification, reference being had to the accompanying drawings, forming a part thereof.

Fig. 1 is a front perspective view of a typewriter cabinet desk showing my new design.

Fig. 2 is a view showing the desk in closed position.

I claim:

The ornamental design for a typewriter desk cabinet, as shown.

JOHN HERZOG.
